UNITED STATES PATENT OFFICE.

CHAS. W. S. HEATON, OF BELLEVILLE, ILLINOIS, ASSIGNOR TO JABEZ J. PIGGOTT AND HENRY RENTCHLER, OF SAME PLACE.

IMPROVEMENT IN CULTIVATORS.

Specification forming part of Letters Patent No. 38,261, dated April 21, 1863.

To all whom it may concern:

Be it known that I, C. W. S. HEATON, of Belleville, in the county of St. Clair and State of Illinois, have invented a new and useful Improvement in Cultivators for Growing Crops; and I do hereby declare that the following is a full, clear, and exact description of the same, reference being had to the accompanying drawings, forming part of this specification, in which—

Figure 1 is a rear view of my improved cultivator. Fig. 2 is a longitudinal section, and Fig. 3 a plan, of the same.

Similar letters of reference in the several figures indicate corresponding parts.

This invention relates to an improvement in the cultivator patented by myself under the name "Phenix Cultivator," this being denominated the "Climax Cultivator."

To enable others skilled in the art to make and use my invention, I will proceed to describe the same with reference to the drawings.

A is a strong truss-frame, approximating in form to the letter **W** when viewed from front or rear, and to the figure of a triangle when viewed from either of its sides. This frame is formed by arranging the timbers *a a* vertical, timbers *b b* inclined, and timbers *c c* both inclined and converging toward one another as they rise, as represented. Such system of timbers is supported at top by one another and by cross-timbers *d d*, as shown. At bottom they are supported in part by one another and by longitudinal beams *e e* and short axles *f f* of the propelling-wheels *g g*, as shown. By this construction I secure an open elevated frame of great strength and little weight.

In order to support the axles *f f* on both the inner and outer faces of the wheels *g g*, I add a vertical timber or hanger, *i*, to each of the extremities of the truss-frame, such timbers being bolted to the cross-beams *d d* and extended down and fastened on the outer extremities of the axles, as shown. The axles may have screw-threads cut on both their inner and outer ends and receive clamping-nuts *j j* thereon, as shown.

In order to support the front ends of the shovel-beams *B B' B'*, a slotted cross-piece, *C*, is fastened to the front end of each of the beams *e e*, and in order to provide a means of

hanging the shovel-beams on pivots *l l*, short longitudinal timbers *k k'* are fastened to the inner ends of the cross-pieces *C C*, as shown.

Two beams, *B*, may be pivoted to each of the timbers *k k'*, as shown, or one beam may be linked to the beam and another linked to the cross-pieces *C*. In any case all of the beams in the one cultivator must or should be hung so as to be pendant on one plow. I have merely shown different ways of making pendant the beams for the purpose of guarding against obvious changes that might be made in this respect. The shovel-beams thus hung are free to rise and descend at their rear ends, and in order to control these ends I arrange rollers *m m* in rear of the cross-timbers *e e* of the truss-frame and attach foot-levers *n n* to the pivots *l* of the shovel-beams, and then attach cords *o o* to the rear of the shovel-beams, pass such cords up around the rollers *m m*, and fasten their ends to the levers, as shown. Curved rods *p p* may also be attached to the shovel-beams, and the same pass up in front of a notched bar, *q*. These rods would act as guides, and, with the bar, as lateral stops whenever necessary. They might also be used as a hand means for adjusting the shovel-beams both laterally and up and down.

The shovel-beams might be controlled by a hand-lever such as shown at *r*; but in the construction of the one cultivator the controlling devices for the shovel-beams must be all constructed on one plan. I have merely shown several plans with a view of guarding against obvious changes that might be made.

The shovel-standards *s* are slotted and attached by pivots to their beams, so as to be adjusted more or less steep or inclined. The beams are made of two pieces, one of which forms an angle with the other. There may be an adjustable brace used in connection with the double beam and slotted shovel-standard, as shown at *t*, to deflect the trash, &c. The slot *s'* of the standards *s* allow of the pin *s''* being set lower on the upper piece of the double beam, so also do the holes *s'''* in the brace *t*.

In order to adjust the forward ends of the shovel-beams laterally, the cross-pieces *C C* are provided with the slots *C' C'* and confined by joint-bolts *C'' C''*, and in order to brace these cross-pieces *C C*, and at the same time not in

terfere with their lateral adjustment, a linked brace-rod, E, is extended from the axle to the outer end of each of the cross-pieces. The joint or link-eye F of this rod allows the rod to accommodate itself to the adjustment given to the cross-pieces C C. The rods might be loosely fitted on the axles and work in slots *u* in the cross-pieces, and thus the joint be dispensed with. The rods brace the machine and act as guards to prevent the wheels breaking down the corn.

I attach the single-trees H H to a chain, I, which runs over high-placed pulleys, J J, of the truss-frame, down under low-placed pulleys K K of said frame, and horizontally through adjustable eyes of the cross-pieces C C, as shown. By this arrangement I obtain a draft from a low point and single single-trees, and still have that draft act from a high point centrally upon the whole structure in a manner to prevent throwing up of the shovels out of the ground.

In this cultivator I employ the long poles or tongues K' K', and also the flexible or jointed neck-yoke M, patented to myself at a previous date, and in addition thereto I employ a long central top reach, L. This reach extends from the top of the truss-frame to the neck-yoke in the manner shown.

To take the weight off of the rear back support M, I provide a jointed frame, N, and fasten or pivot its lower part to the cross-pieces C C, its upper part having the reach fastened to it, as shown.

On the rear end of the reach the driver's seat O is mounted, so as to be adjustable. When the driver is on this seat his weight serves to hold up the forward ends of the long poles K' K', as the neck-yoke is attached to the poles and the reach to the neck-yoke.

In operating with this machine the horses are placed outside of the tongues or poles, and the poles inclose the growing crops and prevent the horses trampling upon the same. The cultivator-shares stand two on one side of the row and two on the other side. If a straggling

blade of corn should come in line with the shares, the operator adjusts the shares so as to steer clear of the same.

What I claim as my invention, and desire to secure by Letters Patent, is—

1. The truss-frame A, constructed in the manner described, in combination with short axles and vertical outside hangers, *i i*, as and for the purpose set forth.

2. The guard-brace E, arranged and operating substantially as described.

3. The combination of the long tongues or poles K' K', neck-yoke M, reach L, and brace N, substantially as and for the purposes set forth.

4. The combination of the adjustable seat O, reach L, long tongues K' K', neck-yoke M, and brace N, substantially in the manner described.

5. A shovel-beam formed of two parts, B B', which make an angle, in combination with a slotted standard, *s*, which is adjustable, substantially as and for the purpose set forth.

6. The combination of the jury-brace *t*, which is adjustable, with the double beam B B' and slotted standard *s*, substantially as and for the purpose set forth.

7. The arrangement of the foot-levers *n*, curved bars *p p*, notched cross-piece *q*, roller *m*, and cords or chains *o*, substantially as and for the purpose set forth.

8. The arrangement of the slotted adjusting pieces C, pendent share-beams, and draft device I, with single single-trees, and frame A and outside hangers *i i*, in the manner and for the purpose described.

9. The combination of the slotted pieces C, brace-rod E, frame A, and pendent share-beams, substantially as and for the purpose set forth.

CHAS. W. S. HEATON.
